SUPPORT STAND FOR AN OFFICE MACHINE

Wayne W. Good, Sturgis, Mich., assignor to Harter Corporation, Sturgis, Mich., a corporation of Michigan

Filed May 20, 1965, Ser. No. 85,369

Term of patent 14 years

(Cl. D33—14)

FIG. 1 is a perspective view of the stand taken from the rear, showing my new design.

FIG. 2 is a perspective view taken from the front; and

FIG. 3 is a perspective view taken from the rear showing the leaves in extended position.

The dominant features of my design are shown in full lines and reside in the extensible leaves which constitute nesting side panels when folded and form dropped wings when raised, all as shown.

I claim:

The ornamental design for a support stand for an office machine, substantially as shown and described.
